UNITED STATES PATENT OFFICE.

BARTOLOME APRIL, OF AZMOOS, SWITZERLAND.

AUTOMATIC COUPLING FOR RAILROAD-VEHICLES.

SPECIFICATION forming part of Letters Patent No. 725,649, dated April 21, 1903.

Application filed August 11, 1902. Serial No. 119,296. (No model.)

To all whom it may concern:

Be it known that I, BARTOLOME APRIL, a citizen of the Swiss Republic, residing at Azmoos, canton of St. Gall, Switzerland, have 5 invented certain new and useful Improvements in Automatic Couplings for Railroad-Vehicles, of which the following is a specification.

With automatic couplings for railroad-vehicles the danger to the life of the railway-servants, which always attends hand-coupling, is avoided, but in addition automatic couplings have considerable working advantages.

15 The object of the present invention is to arrange the separate parts of the automatic coupling on the vehicle in such a manner that they do not interfere with the operation of couplings of the ordinary kind, so that a car 20 provided with the automatic coupling can be coupled as before to cars provided with the old form of couplings.

This automatic coupling is so constructed that the concussion of the buffers when two 25 cars meet first places the coupling-links of both cars in such a position that said links can respectively fall onto two catch-hooks of the opposite coupling, which are adapted to be released from the sides of the cars and 30 movable in vertical planes. Simultaneously, therefore, a double connection of the cars to be coupled is effected—that is, if both cars are provided with the new device. The uncoupling is effected from the sides of the cars, 35 the catch-hooks of both cars being rotated against the pressure of springs, which bear on them respectively until the coupling-links are disengaged therefrom.

The annexed drawings illustrate one form 40 of the invention as an example.

Figure 1 is a vertical section on line A B of Fig. 2, showing the ends of two cars coupled together, both being provided with the improved coupling. Fig. 2 is a part plan view 45 thereof.

The two buffer-rods of each vehicle are connected to each other at the bottom by a cross-bar *a*, bent at several points, so that concussions of the said rods are communicated to 50 the cross-piece. The cross-piece is provided at the side of the central axis of the wagon with a fixed arm *b*, extending away from the

end of the wagon, the said arm *b* carrying a hinged finger *c*, adapted to move upward on a hinge-pivot, but not downward. Above the 55 arm *b* the coupling proper is arranged, consisting of two hinged links *e* and *f*, the inner link *e* being fixed to the uncoupling-shaft *g* and provided with a downwardly-extending support *h*, which before the coupling of two 60 cars first rests on the end of the finger *c*. The link *f* is the actual coupling-link, within reach of which is arranged the releasable catch-hook *i* of the other coupling. The length of the support *h* is preferably so chosen that the 65 link is supported at the angle shown by the dotted line *x* on the right of Fig. 1, so that the coupling-link *f* will be caused by even a slight concussion to fall onto the hook of the coupling of the other wagon. The hinge *z*, 70 which connects the two links *e* and *f*, is so constructed that the said links normally form an extended angle and that even with very powerful concussions no throwing over of the coupling-links is possible.

75 The shaft *g* is provided at each end with a handle *k* and passes through a guide *n*, suspended from the draw-rod *l* below the old drag-hook *m*. At one side of the central axis of the wagon this shaft *g* carries the catch-hook *i*, below which is arranged a powerful spring *o*, which tends to push the hook upward again when the latter has been rotated out of its position by means of the shaft *g*. The latter may be provided with small toothed 80 wheels *p*, each of which gears with a toothed segment *q*, placed on the wagon to facilitate the rotation of the shaft.

85 Before two vehicles provided with the automatic coupling device meet the coupling-links *e f* of both rest on the finger *c* of the arm *b*, carried by cross-piece *a*, and occupy a somewhat-inclined position. (Indicated in Fig. 1 by dotted lines.) When the vehicles meet, the buffers are pushed inward, and with 90 them the cross-bar *a* with its arms *b* and *c*. The links *e f* are thus deprived of their support, and the outer coupling-link *f* immediately falls over the hook *i* of the other coupling before the reaction of the buffer-springs 95 takes place. Subsequent concussions which may occur have no other effect than the folding upward of the links *c*. To uncouple the vehicles, the shaft *g* is rotated by means of 100

the handle or handles *k*, the hook *i*, fixed to the said shaft, being moved downward in a vertical plane against the pressure of the spring *o* acting thereon, whereupon the link *f* of both couplings is released. When the two vehicles have been moved apart, it only remains to place the links *e* *f* on the finger *c*.

It is quite simple to couple a vehicle provided with this automatic coupling to one with an ordinary coupling, since, as already mentioned, the hook *i* and links *e* *f* of each coupling are arranged at one side of the longitudinal axis of the vehicle, and therefore do not in any way interfere with the operation of the usual right-and-left screw-spindle links of the old form of coupling.

The handles *k*, fixed to the shaft *g*, may be made sufficiently long to come within reach of the brakeman, so that he may rotate the shaft while traveling, and thus uncouple the wagons, if desired.

I declare that what I claim is—

1. The combination with a railroad-vehicle having buffers of a rotatable horizontal shaft mounted transversely on the vehicle, a double-hinged link carried by said shaft at one side of the central axis of the vehicle, a catch-hook rigidly connected to said shaft adapted to be engaged by the double link of the opposite vehicle and to be rotated in a vertical plane to uncouple the vehicles, means for supporting the double link in the uncoupled position, means in connection with the buffers for withdrawing said supporting means on two vehicles coming together, means for rotating the aforesaid transverse shaft and means for returning the catch-hook to its original position after uncoupling, substantially as described.

2. The combination with a railroad-vehicle

having buffers of a cross-bar connected to said buffers, a rotatable horizontal shaft mounted transversely on the vehicle, a double hinged link carried by said shaft at one side of the central axis of the vehicle, a catch-hook rigidly connected to said shaft and adapted to be engaged by the double link of the opposite vehicle and to be rotated in a vertical plane to uncouple the vehicles, means carried by said cross-bar for supporting said double link in the uncoupled position, means for rotating the transverse shaft and means for returning the catch-hook to its original position, substantially as described.

3. The combination with a railroad-vehicle having buffers of a cross-bar connected to said buffers, a horizontal arm carried by said cross-bar, a finger hinged to said arm, a rotatable horizontal shaft mounted transversely on the vehicle, a double hinged link carried by said shaft at one side of the central axis of the vehicle a catch-hook rigidly connected to said shaft adapted to be engaged by the double link of the opposite vehicle and to be rotated in a vertical plane to uncouple the vehicle, a supporting-rod carried by said double link and normally bearing on the aforesaid finger, means for rotating, guiding and facilitating the rotation of the transverse shaft and a spring for returning the catch-hook to its original position after uncoupling, substantially as described.

In witness whereof I have signed this specification in the presence of two witnesses.

BARTOLOME APRIL.
